US00D675396S

(12) **United States Design Patent**
Tham et al.

(10) **Patent No.:** **US D675,396 S**
(b4) **Date of Patent:** **** Feb. 5, 2013**

(54) **EDIBLE ITEM**

(75) Inventors: **Karin Tham**, Hannover (DE); **Carsten Polke**, Wunstorf (DE); **Reinhard Schmidt**, Hannover (DE)

(73) Assignee: **Bahlsen GmbH & Co. KG**, Hannover (DE)

(**) Term: **14 Years**

(21) Appl. No.: **29/385,963**

(22) Filed: **Feb. 23, 2011**

(30) **Foreign Application Priority Data**

Aug. 23, 2010 (EM) 001745951-0001

(51) **LOC (9) Cl.** **01-01**

(52) **U.S. Cl.** **D1/128**

(58) **Field of Classification Search** D1/100-199; D30/160; D21/385-386; D24/101-104; D28/8.1; D11/90; 426/3-6, 76, 87, 89, 94-95, 426/100-104, 122, 128, 136, 138-139, 144, 426/249, 274, 293, 302, 305-307, 383, 438-442, 426/464-474, 460, 450-451, 496-497, 502-504, 426/512, 515-518, 543, 557, 549-550, 556, 426/559, 514, 660, 623, 619, 805, 806, 808, 426/499, 572; 428/15

(57) **CLAIM**

We claim the ornamental design for an edible item, as shown and described.

DESCRIPTION

FIG. 1 is a perspective view of an edible item.

FIG. 2 is a top view of the edible item shown in FIG. 1.

FIG. 3 is a bottom view of the edible item shown in FIG. 1.

FIG. 4 is a front view of the edible item shown in FIG. 1.

FIG. 5 is a rear view of the edible item shown in FIG. 1.

FIG. 6 is a left side view of the edible item shown in FIG. 1; and,

FIG. 7 is a right side view of the edible item shown in FIG. 1. The broken lines illustrating the environment form no part of the claimed design. The broken lines which define the bounds of the claimed design form no part thereof.

1 Claim, 5 Drawing Sheets
